DEVICE FOR INDUCING SLEEP AND REST

Frank H. Wiesman, Mount Healthy, Ohio

Application February 26, 1952, Serial No. 273,399

6 Claims. (Cl. 340—384)

1

This invention relates to a device or apparatus for inducing sleep and rest, and is adapted particularly for use in noisy surroundings, or by persons, including infants, whose rest or sleep may be interrupted more or less easily by noises of various types or intensities. The device of the invention operates upon the principle that a pleasing and harmonious steady sound or vibration, adjusted to the temperament of any given individual and located within hearing distance, will induce relaxation and sleep in an atmosphere of disturbing noises or vibrations which may be more intense than the tone or vibratory effect of the sleep-inducing device.

An object of the invention is to provide a device for inducing sleep and rest, which effectively nullifies disturbing noises of the type which usually interfere with human relaxation.

Another object is to provide a simple, inexpensive, and trouble-free device for the purpose stated, which is portable and of light-weight construction, so that it may be used wherever electric power is available.

Another object is to provide a device of the character referred to, which may be adjusted as to pitch and intensity, to soothe and relax the nervous systems of individuals that are differently constituted with respect to emotional characteristics.

A further object of the invention is to provide a device for the purposes stated, the use of which cannot be considered harmful to the individual, and therefore need not be used under the supervision or observation of a physician.

Another object is to provide a novel method of inducing sleep and rest.

The foregoing and other objects are attained by the means described herein and illustrated upon the accompanying drawing, in which:

Figure 1 is a front elevational view of the device of the present invention, part broken away to show certain details of construction.

Figure 2 is an end elevational view of the same.

Figure 3 is a top plan view of the device, with the cover removed.

The device herein disclosed has proven beneficial to the general health of individuals who experienced difficulty in acquiring sufficient restful sleep, due to the disturbing effects of objectionable common noises usually existing within or outside a dwelling. For the individual who finds it necessary to acquire relaxation and sleep during the daytime, when innumerable forms of noise are especially prevalent, the device of the invention is of inestimable value as a sleep in-

ducer; however, its use is appreciated also by sensitive individuals whose relaxation period occurs at night, but who nevertheless experience difficulty in obtaining uninterrupted restful sleep.

Recent observations appear to indicate also that the device may possess therapeutic value for individuals who suffer from certain types of ailments or deficiencies which have a disturbing effect upon the sleeping habits of the patient. Thus, the device is suited for hospital use, as well as for home use. In fact, the circumstances and conditions under which the benefits of the device may be enjoyed are practically unlimited, as the user's experiences therewith will indicate.

Referring to the accompanying drawing, the device will be seen to comprise a box having front and rear upstanding walls 5 and 6, end walls 7 and 8, and a substantially flat bottom wall or face 9. The box has an open top which normally is closed by means of a flanged cover or lid 10. The box and its cover may be constructed of metal, wood, plastic or any other suitable material to house the constituents of the device. The cover normally may be fixed over the open top of the box in any suitable manner, as by means of screws or other fasteners 12.

Means are provided within the box for setting up audible vibrations, which are adjustable as to pitch and intensity, said means being preferably electrically operated. In the form of device disclosed, the vibration generating means operates with alternating electric current, however, it is to be understood that direct current could be employed by modifying the device to include a suitable converter in well known manner, to supply proper electric pulsations for energizing vibration generating means. For the sake of simplicity of explanation, the device will be disclosed herein as one which operates with the use of alternating electric current of customary frequency, which ordinarily ranges between 40 and 60-cycles.

Within the box is a substantially flat vibratory plate 14, which preferably is of a resilient metal having a high hardness characteristic, this plate being adapted to rest loosely upon the inner face 15 of the bottom wall of the box. The plate 14 accordingly is made slightly smaller in size than the box bottom wall. Near one end of the plate there is mounted, by means of screws, rivets or other fasteners 16, an electric vibrator or buzzer which is capable of emitting audible vibrations when energized with a suitable alternating or pulsating electric current. Since the vibrator or buzzer may be of ordinary design and construc-

tion, it is herein disclosed in conventional manner, as a closed casing. In accordance with common practice, the vibrator or buzzer 17 is provided with the usual binding posts 18 and 19 for electrical connection purposes.

At or near the opposite end of plate 14, there is mounted a transformer, indicated conventionally at 20, the secondary winding of which terminates at binding posts 21 and 22. The primary winding of the transformer has connection with an electric outlet or socket 23, into which may be plugged a suitable extension cord supplying electric current to the primary winding of the transformer. The transformer is to be mounted firmly upon the plate 14 in any appropriate manner, as by means of screws, bolts or rivets 24. The socket 23 is accessible through an opening 25 formed in one of the end walls of the box.

One of the upright walls, for example the front wall 5, has mounted interiorly thereof a rheostat 26 of the adjustable type, the resistance value of which may be manually controlled by means of a knob 27 accessible at the front wall of the box. The rheostat includes the usual binding posts or terminals 28 and 29. To electrically connect the elements 20, 26 and 17, one conductor 30 has its ends fixed to the binding posts 22 and 28, a second conductor 31 has its ends secured to the binding posts 29 and 19, and a third conductor 32 connects the binding posts 18 and 21, thereby placing the rheostat and the vibrator in series connection with the low voltage secondary winding of the transformer. With ordinary house current supplied at the socket 23, a proper low voltage current is supplied to the vibrator or buzzer for energizing same, thereby resulting in the production of audible vibrations. The tone quality of the vibrations emitted may be regulated by means of the rheostat 26, to suit the pleasure of the user of the device.

In addition to regulating the tone of the vibrator or buzzer 17, the invention contemplates means for regulating the intensity of the tone for the attainment of a pleasing and harmonious steady sound. The intensity control means may consist of a rigid metallic rod 33, upstanding upon the plate 14 and firmly attached thereto, as by means of a welding or peening operation. Whereas the lower end of the rod is fixed to the plate 14 at the location 34, the upper end thereof is extended through an aperture 35 in the cover 10, and is provided with a screw thread 36 adapted to engage the internal screw threads of a control knob 37 which rests upon the upper surface of the lid or cover 10. By preference, suitable yielding means is provided to gently urge the vibratory plate 14 into flatwise contact upon the bottom wall 9 of the box, without substantially dampening the plate vibrations. One form of means for so depressing the plate 14, may consist of a spiral compression spring 38 which surrounds the rod 33, opposite ends of the spring bearing upon the plate 14 and the under surface of cover 10.

From the foregoing, it readily will be understood that the tone of the vibrator or buzzer 17 may be regulated by means of the rheostat 26, while the intensity of the sound emitted may be controlled by manipulating the nut or knob 37 which varies the force of contact of plate 14 upon the bottom wall of the box. By means of the adjustments referred to, a user of the device may obtain therefrom a steady audible sound which is pleasing to and harmonious with his

own individual temperament. Such a sound so regulated and tuned, located within hearing distance of the user will be found to induce restful relaxation and sleep, and will effectively nullify extraneous noises which otherwise would interrupt sleep. For most effective results, the device should be placed within a few feet of the user's ear, however, the device can be so adjusted as to serve a number of individuals confined to a room, as in a hospital ward, where the persons to be benefited may be located at a considerable distance from the device. As was previously pointed out herein, the circumstances and conditions under which the benefits of the device may be enjoyed are practically without limit.

If desired, certain of the walls of the box, or perhaps the lid or cover, may be provided with a series of openings or louvers 40, to permit the escape of sound from the box while at the same time serving as vents for the release of any heat that may be generated by the transformer and the rheostat incident to extended usage.

It is to be understood that various modifications and changes may be made in the structural details of the device, within the scope of the appended claims, without departing from the spirit of the invention. For example, the socket 23 may be dispensed with if desired, by making an electric cord connection with the primary winding of the transformer; and if an electric switch is desired, same may be applied at any convenient location, or incorporated in the rheostat.

What I claim is:

1. A device for inducing restful sleep in a subject person, which device comprises in combination, a box including a substantially flat wall, a vibratory substantially planar plate in flatwise contact upon said wall, an electric buzzer fixed upon a face of said plate free of contact with said box wall, and means accessible exteriorly of the box for varying the force of contact between the vibratory plate and the aforesaid wall of the box.

2. A device for inducing restful sleep in a subject person, which device comprises in combination, a box including top and bottom walls, a vibratory substantially planar plate, means for suspending said plate from the top wall in flatwise contact upon said bottom wall, a vibration generating means fixed upon said plate for transmitting vibrations thereto, and means accessible exteriorly of the box for varying the force of contact between the vibratory plate and the bottom wall of the box.

3. A device for inducing restful sleep in a subject person, which device comprises in combination, a box including an apertured top wall and a bottom wall, the bottom wall being substantially flat, a vibratory substantially flat plate slightly smaller in dimensions than the box bottom wall, an adjusting rod having one end thereof firmly fixed to the vibratory plate, and an opposite threaded end projecting through the aperture of the top wall, an adjusting nut threadedly engaging the threaded end of the rod, said nut resting upon the top wall and serving thereby to suspend the rod and the vibratory plate thereto attached, with the plate in flatwise contact upon the bottom wall, and an audible vibration generating means fixed upon the vibratory plate for imparting vibrations thereto.

4. A device for inducing restful sleep in a subject person, which device comprises in combination, a box including a substantially flat bottom

wall, a vibratory substantially flat plate smaller in dimensions than the box bottom wall, to rest thereon in substantial flatwise contact, an electrical generator of audible vibrations fixed upon the plate for imparting vibrations thereto, a source of low voltage electric current within the box, an electric circuit including conductors connecting the vibration generator to the low voltage source, an adjustable rheostat connected in the circuit to vary the current output of said low voltage source to the vibration generator, means for controlling the rheostat exteriorly of the box, an upright adjusting rod having one end thereof firmly fixed to the vibratory plate, and an opposite threaded end projecting upwardly away from the plate, an upper apertured support for the rod, the aperture of which support loosely receives the threaded end of the rod, a rotary adjusting nut threadedly engaging the threaded end of the rod, said nut resting upon the support and suspending the rod and the vibratory plate thereto attached, with the plate in substantial contact upon the bottom wall of the box.

5. A device for inducing restful sleep in a subject person, which device comprises in combination, a box including a substantially flat wall, a vibratory substantially flat plate in flatwise contact upon said wall, an electrical generator of audible vibrations fixed upon the plate for imparting vibrations thereto, a source of low voltage alternating electric current within the box, an electric circuit including conductors connecting the vibration generator to the low voltage source of current, an adjustable rheostat connected in

the circuit to vary the current output of said low voltage source to the vibration generator, means for manually adjusting the rheostat exteriorly of the box, and adjustable means accessible exteriorly of the box for varying the force of contact between the vibratory plate and the box wall upon which said plate rests in flatwise contact.

10 6. In a device of the class described, the combination of a box including a substantially flat wall, a selectively movable flat plate substantially covering and resting lightly upon said box wall for movement relative thereto, an electric buzzer rigidly secured to a face of said plate and movable therewith, electric conductors electrically connecting the buzzer to a source of pulsating electric current, and a variable resistor connected in series with the buzzer and the source of electricity, for varying an operating characteristic of the buzzer, and adjustment means for selectively moving the plate and the buzzer unitarily toward and from the box wall.
